UPHOLSTERING MACHINE

Albert Shifrin, Baltimore, Md.

Application June 18, 1949, Serial No. 99,935

8 Claims. (Cl. 45—138)

1

This invention relates to the making of upholstery and tufted materials for cushions, sofas, and the like and particularly to a machine for doing this kind of work.

The conventional method of manufacturing upholstery is by hand methods that are laborious, require considerable skill and experience, and cannot be done with a high degree of uniformity and accuracy. Further the wear and tear on the material required by the hand methods is considerable, and is roughly estimated to be equivalent to several days' ordinary usage, because of the necessary handling, pulling and pushing over surfaces or tables, which is in excess of that required in the manufacture of an upholstered article in this invention. Further such handling is more or less inconvenient, and where it involves the placement of the unfinished materials on the hands and knees of the worker sometimes having to be augmented by weights and other extraneous articles, requires considerable manipulation in front of him, that makes the work difficult and physically laborious to him. When the partly finished cushion or upholstery is compressed, it is accomplished manually, and varies with the skill, strength and weight of the worker. Further the hair packing or its equivalent is hard to fix in the article by hand, and when it comes to placing the buttons at the bottom of the depressions in the upholstery, further difficulty is experienced in their attachment. Other difficulties and inconveniences arise in this manual operational practice, well known to those in this art, and are not mentioned specifically since those already stated are illustrative of the conditions in general.

In this invention, a machine is used that enables the work of forming cushions and padded upholstery to be accomplished in a relatively small proportion of the labor time required by the manual process. More specifically, a specified part of the work that would take five hours by a skilled and experienced workman will be performed on the machine, under the operation of the machine by an operator of mediocre training and experience, in about one tenth of an hour, and the physical effort required of the operators would be on a similar proportion. The machine itself consists of a frame having stationary and rotatable sections on which decks are mounted and made rigid, solid or moveable as may be required. These decks are provided with means that arrange for the attachment of the buttons, as well as facilitate the placement and packing of the padding, and readily adjust the

2

pattern of the upholstery within an extensive field of designs. All this is done with ease and convenience, in a very expeditious manner. To make the positioning of the materials used for developing the upholstery to a finished condition, the frame is made capable of changing the position of a selected deck to an angular plane and outside of the main part of the frame so it will permit access to the upper or lower surfaces of the upholstery in a convenient manner. In other words it eliminates the necessity for the worker to bend over unduly during the assembling. The machine includes an effective pressure mechanism that avoids less effective manual pressure on the upholstery during the packing of the padding, the spreading of the covering over it, and the buttoning work.

It is therefore an object of this invention, to provide a new and improved upholstery making and tufting machine, that will avoid one or more of the disadvantages and limitations of the prior art.

Another object of this invention is to provide a new and improved upholstery machine that will include mechanism for assembling the materials employed for this purpose in a convenient and effective manner, that the upholstery being made will be completed expeditiously and artistically.

A further object of the invention is to provide a new and improved upholstery machine that will enable the materials employed in upholstery and tufting to be laid out in an extensive series of designs to suit any particular requirements, and at the same time permit the operator to connect the buttons required in a facile manner that is labor and time saving.

An additional object of the invention is to provide a new and improved upholstery machine that will perform the functions of compressing the packing, arranging the packing effectively without interfering with the operations of assembling the upholstery that follow.

Still another object of this invention is to provide a new and improved upholstery machine that will enable the various details of the work of upholstering to be done, expeditiously, workmanlike, with limited handling, and with a minimum of labor. Also to provide in such a machine, a design that will limit the amount of space required for its operation as well as avoid the need of a relatively complicated structure.

Other objects will become apparent as the invention is more fully set forth.

The invention also includes in its objects to provide for incidental parts usable in its connec-

tion, to cooperate and coordinate with the different structures of the machine, so as to be replaceable in quantity or type as may be required in the work of upholstering, without interfering or changing the main structure of the machine.

For a clearer comprehension of the invention, its objects and the principles thereof reference is made to the accompanying drawings. These drawings, in conjunction with the following description, outline a particular form of the invention by way of example. And in connection with these drawings, the supporting claims herewith appended indicate the general scope of the invention.

Referring to the drawings:

Figure 1 is a front elevation of an upholstery machine embodying this invention;

Figure 2 is a side view of the machine shown in Figure 1;

Figure 3 is a plan view of the drive mechanism taken along line 3—3 of Figure 1;

Figure 4 is a plan view of the lower journal platform drive mechanism taken along line 4—4 of Figure 1;

Figure 5 is a plan view of the spike deck taken along line 5—5 of Figure 1;

Figure 6 is a plan view of the make-up taken along line 6—6 of Figure 1;

Figure 7 is a sectional view taken through the machine along line 7—7 of Figure 1;

Figure 8 is a sectional view taken through the gripper on the compression deck;

Figure 9 is a sectional detail through the gripper and spike mounted on the spike deck;

Figure 10 is a plan view of Figure 9;

Figure 11 is a detail partly in section of a packing spool;

Figure 12 is a detail in elevation and partly in section of a thimble used on the spike;

Figure 13 is a sectional detail showing the compression deck forcing the upholstery materials into buttoning position;

Figure 14 is a sectional detail with the upholstery buttoned;

Figure 15 is a sectional view through the machine during the process of packing the filling material around the spools on the make-up deck;

Figure 16 is a sectional detail of the rails used on the make-up deck for pinning undercloth into position;

Figure 17 is a sectional view taken through the hand bolts;

Figure 18 is a partial elevation looking sidewise at the machine while the spike deck with spikes and thimbles adjacent make-up deck and passing through the upholstering materials and making ready for the lowering of the compression deck;

Figure 19 is a side elevation partly in section with the tilting deck in tilted position; and

Figure 20 is a side elevation of a needle with button cotter placed therein ready for fastening the upholstery materials together.

Similar reference characters relate to the same parts throughout the drawings.

In the particular construction of the invention shown herein, there is a floor frame 10 arranged to hold the stationary portion of an upholstery machine and be attached to the floor of a building in which it is to be employed. This frame 10 serves as a support for a tilting frame 11 journaled at 13 to a pair of cross-arms 12 transversely arranged on the upper level of the floor frame 10. The stub shafts 14 are extended from somewhat similar cross-arms 15 on the tilting frame 11. The locus of suspension for the tilt-

ing frame on the floor frame is off center and preferably towards the rear of the machine, in order that the tilting of the frame 11 will prevent any portion of the tilting frame from causing interference with other portions of the machine, (especially elements mounted in the floor frame), when the frame 11 is rotated through the maximum travel accorded it. This travel is about 45°, and its purpose is to allow the operator to work on the upholstery manually during any part of its tilting, in a convenient manner or position. The tilting frame is provided with resilient U-formed catches 16 on each of its cross-arms 15 that engage with the cross-arms 12 and clamp thereon when the frame 11 is upright. The catches 16 are resiliently opened up by the extra pull used when the tilting frame is started to a tilting position. The tilting movements are given to the frame 11, by mechanism 17 mounted on a bracket attached to the frame 10 either through a motor 18 or manually by handles fastened to the pulleys of the mechanism. A cable 20 is attached to the frame 11 at one end and loaded with a weight 21 working over a pulley 22 mounted on an adjacent structure 23, so that the tilting frame will be balanced at all points of travel, to facilitate its movement from normal to tilting position.

Floor frame

The floor frame 10 is preferably of a rectangular arrangement of bed-like form, in which the posts 24 are provided at four corners and arranged with flanges 25 for enabling them to be fastened to the ground, by bolts or otherwise. The frame 10 is necessarily rigidly set on the floor to prevent it from being upset by unbalanced loading on it, due to the weight of the upholstery or the positioning of the tilting frame at various angles. It is stiffened by the cross-arms 12. Also struts 27 extending longitudinally between the posts 24, close to the floor, serve to support foundation or platform plates 28, on which journals 29 are mounted. The journals serve as bearings for a shaft 30 longitudinally set in the frame 10. This shaft 30 has a mechanism or train of gears 31 coupled to it to operate it rotatably either manually by handle 19 attached to pulleys 32 and 33 or a motor 18, and belts 36 and 57. The motor is fastened to the platform 28 at a convenient location. A pair of spur gears 34 keyed to the shaft 30 engage in the teeth of vertical racks 35 during their rotation to either raise or lower them. The racks 35 are attached at the upper ends to the framework of a spike deck 37, which is raised and lowered with them during their reciprocation.

The spike deck

The spike deck 37 is an auxiliary framework mounted on and operated within the floor frame 10. It is a rectangular platform with corner tubing guides 38 integrally formed on it. These guides 38 slide along the posts 24 as the deck is raised and lowered and keep it steady in its movement and use. The limits of its travel is the distance between the platform 28 underneath and the angle irons 26 over it. The framework of the spike deck consists of angle-irons 39 on all sides. However the longitudinal angle irons 39 are perforated to provide many closely spaced holes 40 throughout their length. A number of channel bars 41 with their webs downwardly positioned are fastened to the angle-irons 39 at their end portions by bolts 42 and held rigidly transversely across the deck in a specified ar-

angement. The channel bars 41 in addition are drilled at many predetermined spacings to enable gripper couplings 43 to be inserted and located therein. These couplings are similar to to a conventional electrical fitting used for tightly holding unthreaded tubing. It consists of a union having an exterior nut 44 interiorly threaded to mount on an exteriorly threaded shell 46 and in which a spring ring 45 is inserted to hold the tubing clamped securely when the nuts are tightened down on the threaded shell 46. The gripper couplings 43 are inserted in the holes 89 in the channel bars 41 which hold the unthreaded nipple 47 when the nut 91 is tightened on gripper 43. The interior of the unthreaded nipple is preferably filled with plastic 48 or other suitable substance, to hold in each, a long pointed spike 50 extending vertically up from the deck 37 towards a make-up deck 49 which is framed on the angle irons 26 at the bottom of the tilting frame 11. The grippers are arranged to hold the spikes in many designs and spacings to meet the requirements of buttoning upholstery.

The make-up deck

The make-up deck 49 includes the angle-irons 26 and in addition transverse slats 51 loosely laid thereon. These slats are flat bars thick enough to support the upholstery worked thereon, and wide enough to form a substantial resting place for the material to be placed thereon without interfering with the use of the spikes 50 in a manner to be outlined later. The make-up deck 49 also has side rails 52 longitudinally disposed on the angle irons 26 which serve as clamp members for fastening a sheet of burlap 53 therebetween. A series of sharp and short pins 54 project vertically up from under rails 55, secured under the angle irons, through which the pins project so they will insert themselves into the side rails 52 while holding the burlap, so the latter cannot slide off but will be kept taut thereon. Nuts 56 are used to tighten the rails together on the burlap as they are screwed down on nipples 47 attached to the under rails 55. The slats may be of wood or may be of iron magnetized to be attracted to the angle irons 26 to prevent undue slippage during handling, although not obstructing normal positioning of the slats thereon. The slats are placed so that the spikes used will miss and pass between them when raised. They are below the level of the side rails by an amount equal to their thickness.

The use of the make-up deck

When a piece of burlap 53 or undercloth is spread across the make-up deck 49 and held stretched by the pins 47 and 54 it is about an inch above the top surfaces of the slats 51. However pressing on the burlap stretches the burlap so it will lay out approximately flat in the middle and rest on the slats and have an elastic action. When so stretched, the operator takes as many spools 58, (which incidentally are about the same diameter as the nipples 47) as needed and places them about the spikes 50. The spools 58 are cylinders preferably of wood with a central axial passage 59 in which the spikes are disposed, and long enough to surround the spikes for their projecting length. The spools serve as protectors over the spikes to prevent injury to the operator, and also as packing posts for compacting the filling 60 around

them. The operator pushes in the hair or other filler used, with his hands and presses it all around the spool so it will not be loosely spread out. When this is done the filler is tight around the spool, so that, as the spool is removed, it will hold its form and has a space or vortex in it where the spool was. Then usually a cotton pad 61 is placed on the filler. When all this packing and padding is done, an upholstery material 62 forming the finished covering is marked with chalk or other marking materials to designate the locations where the buttons are to be fastened on the pad 61. The operator knows from experience or training just where the spacings for the buttons should be for the design being used for the upholstery, and after they are marked, he notes that the locations correspond with the spikes intended for each location. The spacings on the cover may be $1\frac{1}{2}$ " more between centers than that of the spikes corresponding thereto, so that when the cover 62 is mounted on the spikes, there is a certain amount of apparently loose material between the spikes. This material is taken up during the process of completing the upholstery or tufting because the buttons cause depressions that curve the covering 62 into funnel-like valleys that absorb it.

However at the point arrived at in the process described above, the spikes project through the loose upholstery material 62 and are surrounded by bluntly pointed cylindrical thimbles 63 of wood or other suitable material to cover the points of the spikes. The thimbles 63 also serve as guides of substantial calibre to be used with the reciprocating compression deck 64 mounted on the tilting frame 11.

The compression deck

The compression deck 64, is a movable platform reciprocating on the four corner posts 65, of the tilting frame 11. Its corner sleeves 66 encompass the posts and are guided vertically up and down same when the tilting frame is in its normal vertical position. The deck has angle-iron sides 67 longitudinally on which are inverted cross channels 68 in predetermined spacing fastened thereto by bolts. Gripper couplings 70 similar to those used on the spike deck are installed on the channels 68 and the gripper couplings 70 and spikes 50 are aligned with each other. The grippers 70 hold small pieces of unthreaded tubing termed sleeves 71, and pointed vertically down under the compression deck. There is a sleeve 71 for every spike and in line with it, so that the raising of the spike deck or lowering of the compression deck will allow the spikes 50 to enter their respective sleeves 71. The thimbles 63 on these spikes also pass through the sleeves, and project above the grippers 70. The removal of the thimbles 63, exposes the pointed ends of the spikes which are then lowered so the sleeves 71 will be ready to receive the needles 73 and button cotters 85 at the time of splicing the upholstery cover and burlap together.

The compression deck 64, has U-formed bars 74 holding it adjacent the corner sleeves 66 in rigid attachment. These bars 74 are connected by gear racks 75 reciprocated by pinions 76 keyed to a longitudinally disposed shaft 77. The shaft 77 is supported in a bearing plate 81 attached to posts 65 and bearings 78 mounted on foundation plates 79 transversely secured to the upper struts 90 longitudinally disposed on the tilting frame 11. A suitable gear train mechanism 80 is connected

with the shaft 77 to operate it rotatably at a suitable speed from the motor 18 mounted on the frame.

The frame 11 is tilted on its journals by a spur gear 62 actuated by the motor 18 and gear reducer 93 when a shifter 83 is moved in the proper direction so the gear 82 will engage a segmental gear 91. The shaft 94 is supported by brackets 95, and supports pulleys 32 and 33. The clutch 96 is slidably keyed to the shaft 94 and frictionally contacts pulleys 32 and 33 when the shifter 92 is used to raise or lower the spike deck 37 and compression deck 64.

Operation

The operation of the machine will clarify the functions of each part and the structural requirements involved in their construction.

The machine is placed in normal position, as indicated in Figures 1 and 2, with the tilting frame 11 upright and its catches 16 locked on to the cross-arms 15. The decks 37 and 64 are moved to the lower and upper termini of their respective travels. This leaves plenty of room for the operator to spread the burlap or under-cloth 53, over the make-up deck 49 and have its longitudinal edge portions engaged by the pins 54 and 47 and side rails 52 so it will be tightly stretched. The side rails are clamped by tightening on the hand nuts 56 that hold the assembly together. When this is accomplished, the operator makes ready for the next step. The operator sets the pattern for the buttoning of the upholstery. This consists in the arrangement of the spikes and their holders in the grippers 43 according to the selected pattern. The number of spikes used and spacing thereof determines this pattern. The mechanism 31 is actuated by the motor 18 to raise the spike deck 37 until the spikes 50 pierce the under-cloth 53 and pass through it up to their hilts. The slats 51 before this time have been shifted by hand to avoid the spikes as they are brought up, but still afford a support under the burlap when needed.

The spools 58 are then slipped over the spikes and rested on top of the under-cover 53 and pressed down to bring the burlap against the slats. Then while the spools are in place the operator takes the filling, hair, 60 or whatever is to be used and packed or tamped around the spools to form a cushioning medium for the upholstery. The operator then adds a padding of cotton 61 or the like, over the packed filling and presses it down firmly. In pressing this pad down on the filling, the operator tears it where necessary to provide a hole in it that will enable the pad to slide down over the spools. The slats 31 support the under-cloth 53 while this is being done.

The spools are removed from the spikes and leave spaces or holes in the packing or filling, with simply the spikes 50 projecting up through their axes. The outer finished cover cloth 62, suitably marked with chalk to indicate the loci for the spikes to pierce through, is then placed over the spikes 50 and pushed down on the fillings, packing it slightly into form. Then the pointed ends of the spikes 50 are encased by the thimbles 63 the bottom side of which presses against the cloth 62 to hold it against jumping off the spikes. The compression deck 64 is then moved downwardly through the use of its mechanism 80, and shifter 92, racks 75 and gears 76, until its tubular sleeves 72 are brought over and on the thimbles 63. The thimbles pass through the

sleeves and project above the grippers 70. At the same time, the sleeves 72 engage against the holders of the spikes and clamp the cloth 62 pad 61 and under cloth 53 between them, so that further compression forces the cloth 62 at the spikes into funnel-like depressions and forms the hollowed or curved contour of a cushion with the filling smoothing out the surface. When the compression is considered sufficient by the operator, he stops the compression deck 64 in that position, and lowers away the spike deck 37 so its spikes are retracted to the lower level of the machine out of the way.

After this, the operator causes the tilting mechanism to angularly slant the tilting frame 11 to a position of about 45° and stops it there, or it will stop itself due to the limiting stops from the spikes 50 and puts them aside. He then takes a button cotter 85, of the form shown in Figure 20, and inserts it in the recess 86 of a needle 73 at its butt end until it is enclosed therein, all except the button 87 itself. The pointed end 88 of the needle is passed through the open space 92 in the sleeves 71 and through the semi-formed upholstery, until the button head 87 is tight against the covering 62. The needle is continued through the upholstery at the back or cloth 53, and removed leaving the cotter portion of 85 exposed. The operator then opens the arms of the cotter and presses them flat against the cloth 53 or against a thin washer slipped over the cotter for the purpose, so the button cotter 85 will be fastened in place and that portion of the upholstery secured at the button.

It should be noted that the tilting of the tilting frame 11 is made on its bearings arranged off center so the side of the frame will be brought down into the floor frame in a position that will not cause interference between it and the spikes 50 and cause damage.

The term button cotter is intended to be generic to any fasteners susceptible for use to hold the covers and materials of the upholstery assembly together, and not simply the item indicated in the drawings. The slats 53 do not fall off the layout or make-up deck during the tilting because of the magnetic action as well as the longitudinal strips provided for the purpose to retain them in place. There is no general limit inferred to the type of mechanisms used for moving the decks and the tilting frame, and other arrangements well known just as effective could be utilized, and for the purpose of embracing them, the terms used as mechanisms or means in regard thereto are intended to include them. Likewise the use of the terms burlap, hair, filling and padding while ordinarily designating a specified material is intended to include other fabrics and materials, whether natural or artificial, provided they are usable for the same purpose. The terms upholstery and tufting are intended to include stuffed products in their various forms.

While but one general form of the invention is shown in the drawings and described in the specifications, it is not desired to limit this application for patent to this particular form, as it is appreciated that other forms of construction could be made that would use the same principles and come within the scope of the appended claims.

Having thus described the invention, what is claimed is:

1. An upholstery machine comprising in combination, a frame, a spike deck movably mounted

on said frame, a layout deck mounted on said frame and adapted for the placement of upholstery materials thereon for assembly, piercing means on said spike deck located thereon in a predetermined design, and held so their travel with the spike deck will cause said means to pierce the material for facilitating the placement of cotter buttons therethrough, for binding the materials together in predetermined assembly, spool means mountable on the piercing means and encompassing same to facilitate the packing of filling materials thereabout, and leaving a passage therein when said spool means is removed that the placement of the cotter means will be unobstructed, a compression deck on said frame movably disposed thereon and arranged to reciprocate to and from the layout deck for pressing on said assembled materials to form a predetermined shape thereto to be retained by the fastening of the button coppers thereto, mechanisms for operating the movable decks whereby they act on the materials as aforesaid, means for adjustably holding the spikes to provide for the piercing of divers designs in the materials in accordance with the selection made therefor, sleeve means mountable on the compression deck alignable with the layout of the spike design on the spike deck, whereby the spikes will register therein when brought adjacent the assembled materials and enable the sleeve means to press the materials around the spikes into predetermined depressions to form a hollow or curved form to the upholstery and hold same there until the buttons are fastened thereto.

2. An upholstery machine comprising in combination, a frame, a spike deck movably mounted on said frame, a layout deck mounted on said frame and adapted for the placement of upholstery materials thereon for assembly, piercing means on said spike deck located thereon in a predetermined design, and held so their travel with the spike deck will cause said means to pierce the material for facilitating the placement of cotter buttons therethrough, for binding the materials together in predetermined assembly, spool means mountable on the piercing means and encompassing same to facilitate the packing of filling materials thereabout, and leaving a passage therein when said spool means is removed that the placement of the cotter means will be unobstructed, a compression deck on said frame movably disposed thereon and arranged to reciprocate to and from the layout deck for pressing on said assembled materials to form a predetermined shape thereto to be retained by the fastening of the button coppers thereto, mechanisms for operating the movable decks whereby they act on the materials as aforesaid, means for adjustably holding the spikes to provide for the piercing of divers designs in the materials in accordance with the selection made therefor, sleeve means mountable on the compression deck alignable with the layout of the spike design on the spike deck, whereby the spikes will register therein when brought adjacent the assembled materials and enable the sleeve means to press the materials around the spikes into predetermined depressions to form a hollow or curved form to the upholstery and hold same there until the buttons are fastened thereto, said frame being in sections, one being movable on the other while the latter is stationary to facilitate access to the layout deck by the operator working thereon to complete the making of said upholstery, said movable section being arranged to take a tilting position that said operator can work thereon in an upright position.

3. An upholstery machine comprising in combination, a frame, a spike deck movably mounted on said frame, a layout deck mounted on said frame and adapted for the placement of upholstery materials thereon for assembly, piercing means on said spike deck located thereon in a predetermined design, and held so their travel with the spike deck will cause said means to pierce the material for facilitating the placement of cotter buttons therethrough, for binding the materials together in predetermined assembly, spool means mountable on the piercing means and encompassing same to facilitate the packing of filling materials thereabout, and leaving a passage therein when said spool means is removed that the placement of the cotter means will be unobstructed, a compression deck on said frame movably disposed thereon and arranged to reciprocate to and from the layout deck for pressing on said assembled materials to form a predetermined shape thereto to be retained by the fastening of the button coppers thereto, mechanisms for operating the movable decks whereby they act on the materials as aforesaid, means for adjustably holding the spikes to provide for the piercing of divers designs in the materials in accordance with the selection made therefor, sleeve means mountable on the compression deck alignable with the layout of the spike design on the spike deck, whereby the spikes will register therein when brought adjacent the assembled materials and enable the sleeve means to press the materials around the spikes into predetermined depressions to form a hollow or curved form to the upholstery and hold same there until the buttons are fastened thereto, said frame being in sections, one being movable on the other while the latter is stationary to facilitate access to the layout deck by the operator working thereon to complete the making of said upholstery, said movable section being arranged to take a tilting position that said operator can work thereon in an upright position.

4. An upholstery machine comprising in combination, a frame, a spike deck movably mounted on said frame, a layout deck mounted on said frame and adapted for the placement of upholstery materials thereon for assembly, piercing means on said spike deck located thereon in a predetermined design, and held so their travel with the spike deck will cause said means to pierce the material for facilitating the placement of cotter buttons therethrough, for binding the materials together in predetermined assembly, spool means mountable on the piercing means and encompassing same to facilitate the packing of filling materials thereabout, and leaving a passage therein when said spool means is removed that the placement of the cotter means will be unobstructed, a compression deck on said frame movably disposed thereon and arranged to reciprocate to and from the layout deck for pressing on said assembled materials to form a predetermined shape thereto to be retained by the fastening of the button coppers thereto, mechanisms for operating the movable decks whereby they act on the materials as aforesaid, means for adjustably holding the spikes to provide for the piercing of divers designs in the materials in accordance with the selection made therefor, sleeve means mountable on the compression deck alignable with the layout of the spike design on the spike deck, whereby the spikes will register therein when brought adjacent the assembled materials and enable the sleeve means to press the materials around the spikes into predetermined depressions to form a hollow or curved form to the upholstery and hold same there until the buttons are fastened thereto, said frame being in sections, one being movable on the other while the latter is stationary to facilitate access to the layout deck by the operator working thereon to complete the making of said upholstery, said movable section being arranged to take a tilting position that said operator can work thereon in an upright position.

11

spikes will register therein when brought adjacent the assembled materials and enable the sleeve means to press the materials around the spikes into predetermined depressions to form a hollow or curved form to the upholstery and hold same there until the buttons are fastened thereto, said frame being in sections, one being movable on the other while the latter is stationary to facilitate access to the layout deck by the operator working thereon to complete the making of said upholstery, said movable section being arranged to take a tilting position that said operator can work thereon in an upright position, and thimbles placeable on the spikes for facilitating the entry of the spikes in the sleeve means when the compression and layout decks are brought adjacent each other.

5. An upholstery machine comprising in combination, a frame, a spike deck movably mounted on said frame, a layout deck mounted on said frame and adapted for the placement of upholstery materials thereon for assembly, piercing means on said spike deck located thereon in a predetermined design, and held so their travel with the spike deck will cause said means to pierce the material for facilitating the placement of cotter buttons therethrough, for binding the materials together in predetermined assembly, spool means mountable on the piercing means and encompassing same to facilitate the packing of filling materials thereabout, and leaving a passage therein when said spool means is removed that the placement of the cotter means will be unobstructed, a compression deck on said frame movably disposed thereon and arranged to reciprocate to and from the layout deck for pressing on said assembled materials to form a predetermined shape thereto to be retained by the fastening of the button coppers thereto, mechanisms for operating the movable decks whereby they act on the materials as aforesaid, means for adjustably holding the spikes to provide for the piercing of divers designs in the materials in accordance with the selection made therefor, sleeve means mountable on the compression deck alignable with the layout of the spike design on the spike deck, whereby the spikes will register therein when brought adjacent the assembled materials and enable the sleeve means to press the materials around the spikes into predetermined depressions to form a hollow or curved form to the upholstery and hold same there until the buttons are fastened thereto, said frame being in sections, one being movable on the other while the latter is stationary to facilitate access to the layout deck by the operator working thereon to complete the making of said upholstery, said movable section being arranged to take a tilting position that said operator can work thereon in an upright position, thimbles placeable on the spikes for facilitating the entry of the spikes in the sleeve means when the compression and layout decks are brought adjacent each other, and needle means for facilitating the placement of the button coppers in the assembly just prior to fastening.

6. An upholstery machine comprising in combination, a frame, a spike deck movably mounted on said frame, a layout deck mounted on said frame and adapted for the placement of upholstery materials thereon for assembly, piercing means on said spike deck located thereon in a predetermined design, and held so their travel with the spike deck will cause said means to pierce the material for facilitating the place-

12

ment of cotter buttons therethrough, for binding the materials together in predetermined assembly, spool means mountable on the piercing means and encompassing same to facilitate the packing of filling materials thereabout, and leaving a passage therein when said spool means is removed that the placement of the cotter means will be unobstructed, a compression deck on said frame movably disposed thereon and arranged to reciprocate to and from the layout deck for pressing on said assembled materials to form a predetermined shape thereto to be retained by the fastening of the button coppers thereto, mechanisms for operating the movable decks whereby they act on the materials as aforesaid, means for adjustably holding the spikes to provide for the piercing of divers designs in the materials in accordance with the selection made therefor, sleeve means mountable on the compression deck alignable with the layout of the spike design on the spike deck, whereby the spikes will register therein when brought adjacent the assembled materials and enable the sleeve means to press the materials around the spikes into predetermined depressions to form a hollow or curved form to the upholstery and hold same there until the buttons are fastened thereto, said frame being in sections, one being movable on the other while the latter is stationary to facilitate access to the layout deck by the operator working thereon to complete the making of said upholstery, said movable section being arranged to take a tilting position that said operator can work thereon in an upright position, thimbles placeable on the spikes for facilitating the entry of the spikes in the sleeve means when the compression and layout decks are brought adjacent each other, needle means for facilitating the placement of the button coppers in the assembly just prior to fastening, and mechanisms for causing said tilting and arranged to position the compression deck and layout deck off center on another section of the frame supporting it, whereby the tilting may be induced without bringing positions of its structure into interference with portions of the spike deck.

7. An upholstery machine comprising in combination, a frame, a spike deck movably mounted on said frame, a layout deck mounted on said frame and adapted for the placement of upholstery materials thereon for assembly, piercing means on said spike deck located thereon in a predetermined design, and held so their travel with the spike deck will cause said means to pierce the material for facilitating the placement of cotter buttons therethrough, for binding the materials together in predetermined assembly, spool means mountable on the piercing means and encompassing same to facilitate the packing of filling materials thereabout, and leaving a passage therein when said spool means is removed that the placement of the cotter means will be unobstructed, a compression deck on said frame movably disposed thereon and arranged to reciprocate to and from the layout deck for pressing on said assembled materials to form a predetermined shape thereto to be retained by the fastening of the button coppers thereto, mechanisms for operating the movable decks whereby they act on the materials as aforesaid, means for adjustably holding the spikes to provide for the piercing of divers designs in the materials in accordance with the selection made therefor, sleeve means mountable on the compression deck alignable with the layout of the spike design on the spike deck,

whereby the spikes will register therein when brought adjacent the assembled materials and enable the sleeve means to press the materials around the spikes into predetermined depressions to form a hollow or curved form to the upholstery and hold same there until the buttons are fastened thereto, said frame being in sections, one being movable on the other while the latter is stationary to facilitate access to the layout deck by the operator working thereon to complete the making of said upholstery, said movable section being arranged to take a tilting position that said operator can work thereon in an upright position, thimbles placeable on the spikes for facilitating the entry of the spikes in the sleeve means when the compression and layout decks are brought adjacent each other, needle means for facilitating the placement of the button coppers in the assembly just prior to fastening, mechanisms for causing said tilting and arranged to position the compression deck and layout deck off center on another section of the frame supporting it, whereby the tilting may be induced without bringing portions of its structure into interference with portions of the spike deck, said materials including filling conventionally used in upholstery, padding, undercloth and covering for producing a filled-in tufted upholstery, the covering being marked for the piercing means over predetermined spacings sufficient to allow for said excess of the same when stretched over the filling to provide said depressions during said buttoning.

8. An upholstery machine comprising in combination, a frame, a spike deck movably mounted on said frame, a layout deck mounted on said frame and adapted for the placement of upholstery materials thereon for assembly, piercing means on said spike deck located thereon in a predetermined design, and held so their travel with the spike deck will cause said means to pierce the materials for facilitating the placement of coter buttons therethrough, for binding the materials together in predetermined assembly, spool means mountable on the piercing means and encompassing same to facilitate to packing of filling materials thereabout, and leaving a passage therein when said spool means is removed that the placement of the coter means will be unobstructed, a compression deck on said frame movably disposed thereon and arranged to reciprocate to and from the layout deck for pressing on said assembled materials to form a predetermined shape thereto to be retained by the fastening of the button coppers thereto, mechanisms for operating the movable decks whereby they act on

the materials as aforesaid, means for adjustably holding the spikes to provide for the piercing of divers designs in the materials in accordance with the selection made therefor, sleeve means mountable on the compression deck alignable with the layout of the spike design on the spike deck, whereby the spikes will register therein when brought adjacent the assembled materials and enable the sleeve means to press the materials around the spikes into predetermined depressions to form a hollow or curved form to the upholstery and hold same there until the buttons are fastened thereto, said frame being in sections, one being movable on the other while the latter is stationary to facilitate access to the layout deck by the operator working thereon to complete the making of said upholstery, said movable section being arranged to take a tilting position that said operator can work thereon in an upright position, thimbles placeable on the spikes for facilitating the entry of the spikes in the sleeve means when the compression and layout decks are brought adjacent each other, needle means for facilitating the placement of the button coppers in the assembly just prior to fastening, mechanisms for causing said tilting and arranged to position the compression deck and layout deck off center on another section of the frame supporting it, whereby the tilting may be induced without bringing portions of its structure into interference with portions of the spike deck, said materials including filling conventionally used in upholstery, padding, undercloth and covering for producing a filled-in tufted upholstery, the covering being marked for the piercing means over predetermined spacings sufficient to allow for said excess of the same when stretched over the filling to provide said depressions during said buttoning, said layout deck including slats magnetically held thereto to avoid excessive moving during the use of this deck and the tilting said slats serving as a support for the undercloth.
